UNITED STATES PATENT OFFICE.

RAYMOND CLIFTON PIERI, SR., OF BELZONI, MISSISSIPPI.

PORTABLE SCREEN CAMPING OUTFIT.

Application filed October 10, 1926. Serial No. 61,786.

This invention relates to improvements in camp outfits particularly to a means for providing a combination table or counter, benches, and bed, arranged in adjustable and foldable relationship with a side wall of the shelter.

A further object of this invention is to provide, in connection with a camp outfit having screened side walls, a foldable device adapted 10 to be adjustably attached to a screened side wall in such a manner that when folded against the wall completely out of the way, the screened shelter tent may be used as a living room without obstruction, and when 15 let down, the hinged legs will act to support the device in the form of a bed, or when a part is raised up and properly supported, a strong table and seat may be provided as desired.

20 Other objects will appear in the following description of the device and as disclosed in the two sheets of drawings herewith made a part of this application.

In the drawings,
25 Fig. 1 represents a perspective view of the portable screen camping outfit in assembled form showing the exterior thereof.

Fig. 2 illustrates a perspective view of a section of the interior of the camping outfit, 30 disclosing the foldable device arranged in the form of a table and bench in its relation to a screened side wall.

Fig. 3 represents a perspective view of a section of the interior of the camping outfit, 35 showing the foldable device arranged in the form of a bed in its relation to a screened side wall.

Fig. 4 illustrates a perspective view of a section of the interior of a camping outfit 40 showing the device in its foldable relationship with a screened side wall.

Fig. 5 represents a sectional, elevational view of a screened frame portion having attached thereto, the arms or bracket portions 45 of the foldable device, a hinged leg section is also shown attached at the end of the detachable arm.

Fig. 6 represents a sectional plan view of a corner connection for the screened side walls 50 showing a method of fastening together by means of using square headed bolts.

Numeral 1 designates a shelter consisting of ordinary tenting material or otherwise and having preferably, foldable portions as 55 at 2, while 3 represents screened side walls having suitably framed portions 4 and 5 held

together by angle sections 6, or fastened together in any other suitable manner. A relatively wide section of suitable material, preferably a board, 7, having a flat surface is 60 adapted to be detachably connected along one of its longitudinal edges to the screened frame work portions 4, by means of hooks 8 having a shank portion 9 and fastened to the under longitudinal edge of the flat section of 65 material 7, the hook portions being adapted to cooperate with an eye 10 screwed into the screened frame work portions 4. At suitable intervals along the opposite longitudinal edge of the relatively wide section of 70 material 7 and underneath thereof, are located leg portions 11 suitably hinged as at 12. At a proper distance below the eye 10 in the screen frame work 4, arm or bracket portions 13 are adjustably and foldably mounted as 75 at 14 by means of an angle 15 or any other suitable fastening device. The outer end of arm 13 is adapted to have foldably attached thereto, by means of hinge or otherwise, leg 80 portions 16. Attached to the upper surfaces of the outer ends of arms 13 is a flat section 17 of suitable material, preferably of a narrower width than the flat section 7. The widths of the two flat sections 7 and 17 depend on the width of the bed desired and the 85 convenient arrangement of the bench and table or counter when the device is adjusted for dining purposes or otherwise.

The corner sections of the screen frame work may be connected by square headed 90 bolts 18 as clearly disclosed in Figure 6.

This invention provides a camping outfit which can easily be made up in any size from 6' to 9' or as large as desired, tables of any 95 lengths may be designed from the length of the cot or bed to the entire length of a screen wall, for that matter, all four sides may be utilized for tables, seats and beds, the height of the usual screen wall is six feet and each screen in common practice is about 3' to 6'. 100

By this invention, it is possible to swing a cot, table or bed to the screen frame for two people if necessary, making it possible for from four to eight people having a place to sleep without using army cots or the like. 105 The support for the usual tent covering, as in this case, consists in one ridge pole and two upright poles, one pole setting back into the tent three feet from the screen door, this pole ordinarily has hooks on it answering for a 110 hat, clothes or general utility rack, the idea of one pole setting back being to allow the

door to swing inward. The tables and seats of a large outfit when converted into a bed would be 26" wide, that is, for one person.

In operation, a table, counter and seat are attached to the screen frames in such a manner that they may be used as an eating counter or otherwise, and when not needed as such, they may be folded against the screen wall entirely out of the way. When a bed is desired, the seat may be let down and the counter or table is removed by lifting upward and placing on the arms of the seat, thereby forming a bed, when the equipment is not being used as a table, seat or bed, it may remain hanging to the screen frame, thereby the screen tent may be utilized as a living room free from mosquitoes, flies, gnats, sand flies and other insects. The original or common large camping outfit has a regular tent covering with all four sides rolled up like curtains, each wall having a canvas side that can be rolled up or let down at will, this, of course, makes both a summer and winter tent. A convenient method for locking the canvas to screen frames is by means of ordinary screw eyes fastened to suitable portions

of the screen frame and adapted to pass through iron button holes in the canvas sections, after which the screw eyes are given approximately one-half turn thereby effectively locking the screen and canvas portions together. 30

What I claim is:

In an adjustable folding device suitable for a table, bed or bench, means for detachably connecting the device to the side wall of a shelter, the device comprising a multiplicity of sections consisting of two portions having relatively wide and flat surfaces, means along one longitudinal edge of one of the flat portions for detachably connecting with the shelter wall, supporting arms hinged to the opposite under side edge thereof, the other flat portion secured to the outer ends of supporting brackets, the opposite ends of the brackets 35 40 45 being detachably connected with the shelter wall supports suitably hinged to the outer ends of the supporting brackets, and positioned underneath the last named flat portion.

In testimony whereof I affix my signature.

RAYMOND CLIFTON PIERI, Sr.
